UNITED STATES PATENT OFFICE.

HENRY J. EDLUND, OF BURLINGTON, VERMONT, ASSIGNOR, BY MESNE ASSIGNMENTS,
TO THE FULLER BRUSH COMPANY, OF HARTFORD, CONNECTICUT, A CORPORATION
OF CONNECTICUT.

DESIGN FOR A BROOM.

Application filed April 13, 1922. Serial No. 1,734. Term of patent 14 years.

To all whom it may concern:

Be it known that I, HENRY J. EDLUND, a citizen of the United States, and a resident of Burlington, in the county of Chittenden and State of Vermont, have invented a new, original, and ornamental Design for Brooms, of which the following is a specification, reference being had to the accompanying drawings, forming part hereof, in which—

Figure 1 is a view in front elevation of a broom showing my new design.

Figure 2 is a view in section on a plane denoted by the dotted line 2 of Figure 1.

I claim:

The ornamental design for a broom shown in the accompanying drawing.

HENRY J. EDLUND.
